UNITED STATES PATENT OFFICE.

RÈIMER THOMS, OF SCHLESWIG, GERMANY.

DOOR-LIFTER.

No. 882,029.

Specification of Letters Patent. Patented March 17, 1908.

Application filed March 12, 1907. Serial No. 362,033.

To all whom it may concern:

Be it known that I, RÈIMER THOMS, a subject of the King of Prussia, and resident of No. 54 Friedrichstrasse, Schleswig, in the 5 Empire of Germany, have invented a new and useful Improved Door-Lifter, of which the following is a specification.

The present invention relates to an improved door lifter.

10 Special objects of the invention are to simplify and cheapen the construction and to render more efficient serviceable and durable in operation devices of the kind referred to.

With these ends in view the invention consists in the novel combination, arrangement and adaptation of parts, all as more fully hereinafter explained, shown in the accompanying drawings and then specifically set out in the appended claims.

20 Figure 1 shows the improved door lifter ready for use. Fig. 2 shows the improved door lifter in the position of rest after raising the door.

The ordinary constructions of the door 25 hinges require to be lubricated from time to time in order to secure noiseless movements of the door. This lubrication generally requires a lifting the door to some extent, so as to open a way for the admission of the lubricant to the hinge pin. By virtue of the considerable weight of the door this lifting operation is very cumbersome and demands a great expenditure of human power. Besides the person lifting the door, a second 35 person is frequently called upon to perform the lubrication, while the door is being held in its raised position.

The present invention obviates these 40 drawbacks and disadvantages in a simple, practicable and efficient manner. It greatly facilitates and simplifies the operations of lifting the door and of lubricating the door hinges.

The essential feature of the invention consists in constructing the improved door lifter in the shape of a two-armed lever, adapted to be actuated by foot-pressure and adapted to automatically hold the door raised, when the lifting movement of the 50 lever is completed. The person, having raised the door, is thus at liberty to move about and to perform at leisure the lubrication of the hinges.

The main body *a* of the door lifter is preferably constructed block-shaped. Attached

to, or integral with, two opposite sides of the main body *a* are the two horns *b*, *c*, which constitute the extremities of the two-armed lever *a*, *b*, *c*. Said horns *b*, *c* extend from the main body *a* a short distance above the bottom surface *f* thereof. The surfaces *h* of the body *a* above the horns *b*, *c* constitute abutment faces for the door, as will be described in detail later on.

The mode of application of the improved door lifter is as follows:—One of the horns (in the example illustrated in the drawings the horn *b*) is pushed with its tip *i* into the gap beneath the opened door and the floor, as shown in Fig. 1. By placing a foot on the 65 second horn and exerting pressure thereon, the two-armed lever *a*, *b*, *c*, whose fulcrum is formed by the edge *d* of the center body *a*, will be turned and consequently the door *e* will be lifted, until the base *f* of the main 70 body *a* lies flatly against the floor *g*, as shown in Fig. 2.

Owing to the force of gravitation and the rotary attachment in the hinges, the door, while being lifted, simultaneously slides 75 along the top surface of the horn *b*, towards the face *h* of the center body *a*, against which it ultimately abuts. It thus shifts the center of gravity into such a position relatively to the fulcrum and leverage of the two- 80 armed lever *a*, *b*, *c*, that the latter is prevented from tilting backwardly, when the pressure of the foot ceases. The door is thus held raised without further manipulations and without the employment of auxiliary 85 appliances.

To provide against indentations in the floor, or in the carpet or other floor covering by the edge *d* constituting the fulcrum, it 90 may be advisable to round said edge *d*. It 95 may, further, be advantageous to construct the member *a* of the improved door lifter in the shape of a hollow body, so as to adapt its interior for the reception of an oil can or other requisites employed in the lubrication 100 of door hinges.

I do not desire to be understood as limiting myself to the detail construction and arrangement of parts as herein shown and described, as it is manifest that variations and 105 modifications therein may be resorted to, in the adaptation of my invention to varying conditions of use, without departing from the spirit and scope of my invention and improvements. I therefore reserve the right to 110

all such variation and modification as properly falls within the scope of my invention and the terms of the following claims.

What I do claim as my invention, and desire to secure by Letters Patent, is:

1. An improved door lifter in the shape of a two-armed lever, adapted to be actuated by foot pressure and adapted to automatically hold the door raised, when the lifting movement of the door is completed, comprising a block-shaped center body *a* and a pair of horns *b*, *c* attached to, or integral with, two opposite sides of the center body *a*, substantially as set forth.
- 10 2. An improved door lifter in the shape of a two-armed lever, adapted to be actuated by foot pressure and adapted to automatic-

ally hold the door raised, when the lifting movement of the door is completed, comprising a block-shaped center body *a* and a pair 20 of horns *b*, *c* attached to, or integral with, two opposite sides of the center body *a*, said horns extending from the side faces *h* at the lower portion thereof but a short distance above the bottom edge *d* of same, substantially as described and for the purpose set forth.

In witness whereof I have hereunto signed my name this 7th day of February, 1907, in the presence of two subscribing witnesses.

REIMER THOMS.
